WARP CLAMP

Burian D. White, Ellenboro, N. C.

Application October 26, 1951, Serial No. 253,281

4 Claims. (Cl. 28—42)

1

This invention relates to a novel one piece warp clamp for clamping warp to a whip roller for holding the warp straight while it is brushed into a portable tying machine and while it is being tied to insure that the warp will be tied straight on a loom so that it will run satisfactorily.

More particularly, it is an aim of the present invention to provide a one piece warp clamp of extreme simple construction which will prevent twisted warp when the warp is subsequently pulled or run over the loom from a warp beam.

Various other objects and advantages of the invention will hereinafter become more fully apparent from the following description of the drawing, illustrating a preferred embodiment thereof, and wherein:

Figure 1 is an end elevational view showing the one piece warp clamp secured to a whip roller and illustrating the location of the whip roller with respect to a warp beam;

Figure 2 is a fragmentary side elevational view of the whip roller with the clamp applied thereto;

Figure 3 is an enlarged cross sectional view taken substantially along a plane as indicated by the line 3—3 of Figure 2, and

Figure 4 is a fragmentary plan view looking toward the upper side of an end of the warp clamp.

Referring more specifically to the drawing, for the purpose of illustrating one application and use of the one piece warp clamp, designated generally 5 and comprising the invention, an end of a warp beam 6 is illustrated in Figure 1 and designated 6 and a whip roller 7 is shown disposed above the warp beam 6 while a portion of a loom rail 8 is illustrated beneath the warp beam. These parts are of conventional construction and constitute no part of the present invention, and the warp beam 6 and roller 7 may be journaled in any suitable supporting structure, not shown.

The warp clamp 5 includes an elongated body portion 9 which may be formed of any suitable material and which may be in one piece or may be formed from three abutting pieces, as illustrated, including an intermediate strip 10 and corresponding side strips 11 which are secured in any suitable manner in abutting engagement to the opposite sides of the intermediate strip 10. The body member 9 has substantially parallel opposite sides 12 and 13 which are disposed at right angles to the outer side 14 of the body member 9. The inner side of the body member 9 is provided with a V-shaped groove 15 which extends from end-to-end thereof and the two

corresponding sides or faces 16 of which are preferably disposed at a right angle to one another and merge at their outer edges with the opposite sides 12 and 13.

5 A relatively thick strip of yieldable material 17, preferably sponge rubber, is suitably secured to each of the groove faces 16 near the outer edge thereof, and said sponge rubber strips 17 extend from end-to-end of the groove 15 and are of a width substantially less than the width of the faces 16 so that each strip 17 has an inner edge spaced a substantial distance from the bed of the groove 15, as best illustrated in Figure 3.

A pair of plates 18 is attached against the side 12 of the body 9, one adjacent each end thereof, by suitable fastenings 19 and each plate 18 is provided at one end thereof with an eye 20 to each of which eyes is fastened an end of a chain or other flexible member 21. The chains 21 are attached at their opposite, free ends to eyes 22 forming the heads of bolts 23. A wing nut 23a is threaded on each of the two bolts 23. A pair of rigid metal plates or strap members 24 are disposed against the outer side 14 of the body member 9 and transversely thereof and in alignment with the plates 18. The strap members 24 are secured by suitable fastenings 25 to the elements 11 of the body member 9 and each strap member 24 has a bifurcated end 26 which projects outwardly from the side 13.

One preferred application and use of the one piece or unitary warp clamp has been illustrated in the drawing. Assuming that a new or filled warp beam 6 has been applied in a position as illustrated in Figure 1 beneath the whip roller 7, in a conventional manner forming no part of the present invention, the warp 27 is extended upwardly from the warp beam 6 in a counterclockwise direction over the whip roller 7, as illustrated in Figures 1 and 3 and is then drawn counterclockwise downwardly around the under part of the warp beam 6 and projects from between the warp beam 6 and the loom rail 8 away from the warp beam. The end of the warp which extends outwardly between the warp beam 6 and loom rail 8 is then pulled until the warp extends straight from the warp beam up and over the whip roller. The body member 9 of the clamp 5 is then disposed on the whip roller, as illustrated in Figures 1, 2 and 3 with the exposed outer faces of the sponge rubber strips 17 engaging against circumferentially spaced portions of the warp 27 which is trained over the whip roller 7. The clamp 5 may be made in various lengths and the body member 9 thereof

is considerably longer than the width of the warp 27, as illustrated in Figure 2, so that when the body member 9 is thus applied to the warp on the upper part of the whip roller 7 the chains 21 will be disposed beyond the side edges of the warp 27. With the wing nuts 23a backed off toward the distal ends of the bolts 23, the chains are extended around the underside of the whip roller 7 in a clockwise direction as seen in Figures 1 and 3 and beyond the side edges of the warp 27 and the bolts 23 are inserted into the slots of the bifurcated strap portions 26, through the open outer ends of said slots, each bolt 23 engaging the strap portion 26 which is disposed in transverse alignment with the chain 21 to which said bolt is connected. The wing nuts 23a are then turned in the opposite direction to draw the bolts 23 upwardly through the bifurcated strap ends 26, since the nuts 23a will bear against the upper surfaces of the furcations of the bifurcated ends 26. The nuts 23a are thus tightened until the chains 21 are drawn tight around the under part of the whip roller 7 to thereby draw the clamp body member 9 downwardly to bring the strips 17 into tight gripping engagement against the whip roller 7 for clamping spaced portions of the warp 27 between said strips 17 and the whip roller 7. The warp or yarn 27 while thus clamped is cut off straight across near the loom rail 8 and the cutoff end of the warp is then pulled back over the clamp 5 and the whip roller 7 is allowed to turn clockwise from its position of Figures 1 and 3 until the clamp is disposed beneath the whip roller. The cutoff end of the warp is then brushed into a portable tying machine and tied, not shown, after which the clamp 5 is removed and the warp beam 6 turned clockwise to take up the slack. The warp is then ready to be pulled or run.

It is to be understood that the foregoing constitutes only one possible use of the unitary warp clamp 5 in conjunction with a portable tying machine and that it may be used in other ways in connection with the tying machine for temporarily clamping the warp to a whip roller to initially position the warp so that it extends straight off of a warp beam over a whip roller and to effectively clamp and hold the warp in a straight condition until it has been tied and is ready to be run. Thus, with the use of the warp clamp 5, the elimination of twisted warp is accomplished since the warp is extended straight from the warp beam and clamped to the whip roller while it is being tied straight on a loom.

Various modifications and changes are contemplated and may obviously be resorted to, without departing from the spirit or scope of the invention as hereinafter defined by the appended claims.

I claim as my invention:

1. A warp clamp of the character described comprising an elongated body member having an inner face, an outer face and opposite sides, said inner face being provided with a groove extending from end-to-end thereof of substantially V-shaped cross section, the two sides of said groove merging with complementary longitudinal edges of the opposite sides of said body member, a strip of cushioning material secured to each

side of the groove and extending from end-to-end thereof, said strips extending to adjacent the outer, remote edges of the sides of the groove and having outer surfaces adapted to bear against circumferentially spaced portions of a whip roller and against a warp trained over the whip roller, a pair of chains each having an end secured to the body member, said chains being secured to one of the sides of the body member one adjacent each end thereof, a threaded bolt connected to the free end of each chain, an adjustable stop threadedly engaging each bolt, a pair of rigid strap members secured to the outer face of the body member, said rigid strap members being disposed transversely of the body member and substantially in transverse alignment with the anchored ends of the chains, said straps having bifurcated free ends projecting from the opposite side of the body member for receiving said bolts, said adjustable stops engaging the outer surfaces of said bifurcated ends and being rotatable for drawing the bolts therethrough for tensioning the chains around the whip roller to draw said cushioning strips towards the whip roller for clamping the warp between the whip roller and cushioning strips.

2. A warp clamp as in claim 1, said body member being formed of a plurality of co-extensive strips including a pair of outer strips and an intermediate strip interposed between the outer strips and secured in abutting engagement thereto.

3. A warp clamp as in claim 1, said cushioning strips being formed of sponge rubber and being of a width substantially less than the width of the groove sides and having outer edges merging with the opposite sides of said body member and inner edges spaced from the bed of said groove.

4. The combination with a whip roller, of a warp clamp comprising an elongated body member having a grooved inner face extending from end-to-end thereof, cushioning strips secured to said grooved inner face and extending longitudinally thereof for engaging circumferentially spaced portions of the whip roller, and flexible attaching means having intermediate portions detachably engaging around longitudinally spaced portions of the whip roller and end portions connected to the body member, one end portion of each of said flexible attaching means being detachably and adjustably connected to the body member and being adjustable for drawing the body member towards the whip roller for clamping warp between the whip roller and said cushioning strips.
